(57) **CLAIM**

I claim the ornamental design for a handle of tool, as shown and described.

DESCRIPTION

FIG. 1 is a perspective view of the handle, showing my design;

FIG. 2 is another perspective view of the handle shown in FIG. 1;

FIG. 3 is a front view of the handle shown in FIG. 1;

FIG. 4 is a rear view of the handle shown in FIG. 1;

FIG. 5 is a left side view of the handle shown in FIG. 1,

FIG. 6 is a right side view of the handle shown in FIG. 1;

FIG. 7 is a top view of the handle shown in FIG. 1;

FIG. 8 is a bottom view of the handle shown in FIG. 1;

FIG. 9 is a cross-sectional view of the handle taken along a line A-A shown in FIG. 5;

FIG. 10 is a cross-sectional view of the handle taken along a line B-B shown in FIG. 5;

FIG. 11 is a cross-sectional view of the handle taken along a line C-C shown in FIG. 5;

FIG. 12 is a cross-sectional view of the handle taken along a line D-D shown in FIG. 5; and,

FIG. 13 is a perspective view of a bit connected to the handle shown in FIG. 1.

The broken lines shown in the drawings are for the purpose of illustrating unclaimed portions of the handle and form no part of the claimed design.

1 Claim, 10 Drawing Sheets
